MATERNITY GARMENT

Ruth M. Mahoney, Santa Monica, Calif.

Application July 16, 1941, Serial No. 402,657

3 Claims. (Cl. 2—76)

This invention relates to clothing and is more particularly concerned with a skirted garment of the type which may be expanded at the waist to accommodate increases in girth of the wearer incident to pregnancy.

To allow for adjustment of the waist of maternity garments, for the purpose of increasing the cross-sectional area thereat, such garments are usually characterized by either an overlapping or pleated construction of the front portion of the skirt. If the pleated construction is used, increases in cross-sectional area are generally effected either by reduction of the number of pleats or by reducing the depth thereof. The overlapping construction, on the other hand, involves simply a change in the location of the fasteners to compensate for physiological development.

Because of the fact that the use of pleats allows for more variation in styling, this type of maternity dress at present enjoys great popularity, the designers of maternity dresses, employing the basic principle of pleats, having developed a wide variety of attractive constructions including concealed pleats, ornamental pleats and combinations of the two. The reason for this activity, of course, is to insure maximum style consistent with satisfactory adaptation to maternity uses.

Although the maternity garment of the pleated type is at present quite popular and is commercially available in a wide variety of styles, there are some features thereof which present difficulties to the user. The principal of these is the maintenance of the hemline in a single horizontal plane.

At the beginning of pregnancy, when the figure is normally proportioned, a well-fitted garment will comprise a certain amount of material back and front extending from the shoulders to the hemline. The dressmaker, in fitting, adjusts this length of material in such a way that the hemline lies in a single horizontal plane. However, as pregnancy progresses with incident enlargement of the abdominal area, the material constituting the front portion of a garment is raised at the waist area causing a pull from the shoulders and the hemline. Since garments are usually supported from the shoulders, the foregoing tendency is in evidence only at the hemline, the result being that the hemline at the front of the skirt is pulled upwardly into an arcuate form while at the back of the skirt it remains in normal position. This change in the level of the hemline makes it necessary for the wearer to

continually unsew the hem of the garment and resew it in correct position.

The hemline problem has not heretofore been solved and known constructions allowing for increases in the cross-sectional area of the skirt at the waist do not, regardless of how effected, provide sufficient compensation to insure maintenance of the initial hemline position.

It is therefore an object of this invention to overcome the foregoing difficulties and to provide a maternity garment of the pleated type characterized by a simple and easy adjustment for maintaining the hemline thereof in a single horizontal plane regardless of the degree of increase of the cross-sectional area of the skirt at the waist.

According to this invention, it is contemplated that the front hemline levels of a skirted maternity garment may be adjusted without sewing and that the adjustment may be made in harmony with an adjustment of the cross-sectional area of the waist thereof.

It is a further object of this invention to vastly improve the styling of maternity garments while concomitantly rendering the same better adaptable to the intended use.

Other objects and advantages of this invention will be apparent upon consideration of the following detailed description in conjunction with the annexed drawing wherein:

Figure 1 is a view in front elevation of a dress constructed in accordance with the present invention;

Figure 2 is a view in section taken along the line 2—2 of Figure 1;

Figure 3 is a view in section taken along the line 3—3 of Figure 1;

Figure 4 is a view in front elevation of a dress embodying a modified form of the present invention comprising four pleats; and

Figure 5 is a view in section taken along the line 5—5 of Figure 4.

Referring more particularly to Figures 1 to 3, inclusive, the garment shown consists of a skirt portion 10 and a blouse portion 11 which may be provided with sleeves 12 of any conventional construction. While it is entirely possible to construct the dress illustrated with integral skirt and blouse portions, as a matter of style a separate waist band 13 is ordinarily used to connect the two.

As can be seen in Figure 1, blouse portion 11 is not intended to completely envelop the body of the wearer, said portion being provided with a centrally located front slit at 14 extending from

the neckline of the dress to the waist band 13. Similarly, the skirt portion 10 is not continuous but includes two front edges 15 and 16 defining a space therebetween. The space between edges 15 and 16 is centrally located in the front of the garment and is in alignment with the slit at 14 so as to form a continuation thereof. Since the garment illustrated in Figures 1 and 2 is shown in fully retracted position, the area between edges 15 and 16 is largely occupied by pleats 17 and 18 comprised of overlapped portions of the material constituting the front portion of the skirt 10.

Overlying the slit at 14 and the space between the folds of pleats 17 and 18 is a continuous front panel 19 which extends from the shoulders to the hemline of the garment. Panel 19 is attached to blouse portion 11 only at two points of support which, as shown, may be a plurality of snap fasteners 20 located on each shoulder of the blouse. Snap fasteners 20 are located in banks of four, each of the three banks shown lying in a different horizontal plane. It is contemplated that only one of these banks be used at any given time and, with the waist line fully retracted as shown in Figures 1 and 2, the uppermost bank will be in operative position, see Figure 3. Ordinarily, only four cooperating snap fasteners 21 need be attached to panel 19 for coaction with the fasteners 20. Although panel 19 is not attached to blouse 11 at any portion thereof except for support by snap fasteners 20, it is sewed to the edges 15 and 16 of the skirt portion 10 as may be seen by reference to Figure 2.

At the waist line, waist band 13 ends at points 22 and 23 and from points 22 and 23 to the central vertical slits of blouse 11 and skirt 10 these latter portions are not connected and hence define therebetween two horizontal slits 24 and 25. At a point overlying slits 24 and 25, panel 19 is provided with a portion 26 overlying and attached to the same. The projecting edges of portion 26 are provided with fasteners 27 intended for co-operation with any one of the fasteners 28 carried by the skirt in order to control adjustably the depth of pleats 17 and 18 and hence the cross-sectional area of the garment at the waist line.

When the dress shown in Figures 1 to 3, inclusive, is used during pregnancy it is first worn with all fasteners attached in the manner shown. Thereafter, as the girth of the wearer increases, the depth of pleats 17 and 18 is reduced. Concurrently with each adjustment of the depth of these pleats a lower set of fasteners 20 is brought into operation thereby lowering the hemline by lowering the upper support for panel 19. Thus, despite increases in girth, the hemline is maintained in a single horizontal plane.

Clearly, a greater or lesser number of fasteners 20-21 and 27-28 may be employed to render finer adjustments. Also it is contemplated that some means be provided for at least partially closing the slit at 14 in blouse 11. For example, one or more tie strings 29 may serve this purpose.

The garment shown in Figures 4 and 5 is essentially similar to the one just described and like parts have been designated by like reference characters. The manner of support of panel 19 from blouse portion 11 is identical to that shown in Figures 1 and 3. At the waist and skirt portions, however, the garment is provided with four instead of two pleats. These pleats are in pairs and are formed by twice doubling the skirt material adjacent edges 15 and 16 thus forming pleats 30, 31, 32 and 33. Of these a portion of

pleats 30 and 31 shows on either side of panel 19, see Figure 4.

At the waist of the garment portion 26 is provided with fasteners 34 cooperating with fasteners 35 attached to pieces 36 and 37 which, in turn, are fastened to pleats 32 and 33. Pieces 36 and 37, as well as portion 26, serve in the construction of Figures 4 and 5 the function which portion 26 alone serves in the construction of Figures 1 and 2. Thus pieces 36 and 37 are also provided with fasteners cooperating with fasteners on waist band 13. These fasteners are designated by the numerals 38 and 39.

The increase of the cross-sectional area of the garment shown in Figures 4 and 5 is effected in much the same way as the increase of the garment shown in Figures 1 and 2. However, pleats 31 and 33 of the garment of Figure 5 have a composite depth about equal to the depth of corresponding pleat 18, see Figure 2. Thus, as pregnancy progresses, first one of the sets of pleats may be let out and then the other. In order to maintain as long as possible the pleasing lines of the construction of Figure 4, pleats 30 and 31 will be the first to be reduced in depth. As before, the continuous central panel 19 is lowered to compensate for the lifting of the hemline thereby maintaining the latter continuously in a single horizontal plane.

While the illustrated forms of the invention have shown the various connections as effected by snaps it is evident that any type of quick detachable fastener may be used.

Having now described the invention in its preferred form, it is understood that variations and modifications may be made therein without departing from the spirit of the invention, and it is desired that the scope thereof be limited only by the appended claims.

What I claim is:

1. A maternity dress comprising, a skirt having two generally parallel edges at the front thereof defining a centrally located space therebetween, a blouse portion, said blouse portion being slit in front from the waist line to the neckline, the slit in the blouse portion being in vertical alignment with the space between the edges of the skirt, and a front panel overlying the slit in the blouse portion and extending from the shoulders thereof to the hemline of the dress, the edges of said skirt being folded back upon themselves and attached to said panel to define two pleats, means connecting the blouse portion to the skirt portion, the connection being interrupted adjacent the slit, a plurality of fasteners connecting the upper edge of said panel to the shoulder portion of said blouse, and a plurality of fasteners for supporting said skirt pleat at different depths to allow for adjustment to accommodate increase in girth of the wearer, said first-named fasteners lying in different horizontal planes to allow said panel to be lowered when the waistline of the wearer increases to insure maintenance of an even front hemline.

2. A maternity dress comprising, a skirt having two generally parallel edges at the front thereof defining a centrally located space therebetween, a blouse portion, said blouse portion being slit in front from the waist line to the neckline, the slit in the blouse portion being in vertical alignment with the space between the edges of the skirt, and a front panel overlying the slit in the blouse portion and extending from the shoulders thereof to the hemline of the dress, the edges of said skirt being folded back upon themselves a plu-

rality of times and attached to said panel to define a plurality of pleats on either side thereof, means connecting the blouse portion to the skirt portion, the connection being interrupted adjacent the slit, a plurality of fasteners connecting the upper edge of said panel to the shoulder portion of said blouse, and a plurality of fasteners for supporting said skirt pleat at different depths to allow for adjustment to accommodate increase in girth of the wearer, said first-named fasteners lying in different horizontal planes to allow said panel to be lowered when the waistline of the wearer increases to insure maintenance of an even hemline.

3. A maternity dress comprising a skirt having two generally parallel edges at the front thereof defining a centrally located space therebetween, a blouse portion, said blouse portion being slit in front from the waistline to the neckline, the split in the blouse portion being in vertical alignment with the space between the edges of the skirt, and a front panel overlying the slit in the

5 blouse portion and extending from the shoulders thereof to the hemline of the dress, the edges of said skirt being folded back upon themselves and attached to said panel to define two pleats, means connecting the blouse portion to the skirt portion, the connection being interrupted adjacent the slit, a plurality of fasteners connecting the upper edge of said panel to the shoulder portion of said blouse, a belt attached to and extending laterally of said panel, said belt being provided with a plurality of fasteners, cooperating fasteners on means connecting the skirt portion and the blouse portion, said fasteners supporting said skirt pleat at different depths to allow for adjustment to accommodate increase in girth of the wearer, said first-named fasteners lying in different horizontal planes to allow said panel to be lowered when the waistline of the wearer increases to insure maintenance of an even hemline.
